US00D964167S

(12) **United States Design Patent** (10) **Patent No.:** **US D964,167 S**
(45) **Date of Patent:** **** Sep. 20, 2022**

(54) **CLOSURE**

(71) Applicant: **Henkel AG & Co. KGaA**, Duesseldorf (DE)

(72) Inventors: **Daniel P. Sterling**, Fairfield, CT (US); **Keith J. Colacioppo**, Harrison, NY (US)

(73) Assignee: **Henkel AG & Co. KGaA**, Duesseldorf (DE)

(**) Term: **15 Years**

(21) Appl. No.: **29/659,510**

(22) Filed: **Aug. 9, 2018**

(51) LOC (13) Cl. **09-01**

(52) U.S. Cl. **D9/443; D9/435**

(57) **CLAIM**

The ornamental design for a closure, as shown and described.

DESCRIPTION

FIG. 1 is a front perspective view of a first embodiment of a closure showing our new design;

FIG. 2 is a rear perspective view thereof;

FIG. 3 is a top plan view thereof;

FIG. 4 is a front side elevation view thereof;

FIG. 5 is a rear side elevation view thereof;

FIG. 6 is a right side elevation view thereof;

FIG. 7 is a left side elevation view thereof;

FIG. 8 is a bottom plan view thereof;

FIG. 9 is a front perspective view of a second embodiment of a closure showing our new design;

FIG. 10 is a rear perspective view thereof;

FIG. 11 is a top plan view thereof;

FIG. 12 is a front side elevation view thereof;

FIG. 13 is a rear side elevation view thereof;

FIG. 14 is a right side elevation view thereof;

FIG. 15 is a left side elevation view thereof; and,

FIG. 16 is a bottom plan view thereof.
